US0D1098427S

(12) **United States Design Patent** (10) Patent No.: **US D1,098,427 S**
(45) Date of Patent: ** Oct. 14, 2025

(54) **CATHETER CONNECTOR**(71) Applicant: **Medline Industries, LP**, Northfield, IL (US)(72) Inventors: **Kelly Molinaro**, Chicago, IL (US); **Christopher J. Miller**, Wilmette, IL (US); **Thomas Hartney**, Chicago, IL (US); **Kevin Colish**, Evanston, IL (US); **Sarah Phelps**, Palatine, IL (US); **Nidaa Ramahi**, Palos Hills, IL (US)(73) Assignee: **Medline Industries, LP**, Northfield, IL (US)(**) Term: **15 Years**(21) Appl. No.: **29/952,963**(22) Filed: **Jul. 18, 2024****Related U.S. Application Data**

(63) Continuation of application No. 29/826,238, filed on Feb. 10, 2022, now Pat. No. Des. 1,041,003.

(51) **LOC (15) Cl.** ..... **24-02**(52) **U.S. Cl.**USPC ..... **D24/129**; D24/133(58) **Field of Classification Search**USPC D24/112-115, 127-130, 133
CPC A61M 25/0136; A61M 25/0097; A61M 2025/0098; A61M 25/0017

See application file for complete search history.

CLAIM

The ornamental design for a catheter connector, as shown and described.

DESCRIPTION

FIG. 1 is a top, front perspective view of a catheter connector in accordance with a first embodiment of our new design;

FIG. 2 is a bottom, rear perspective view thereof;
 FIG. 3 is a front elevation view thereof;
 FIG. 4 is a rear elevation view thereof;
 FIG. 5 is a right side elevation view thereof;
 FIG. 6 is a left side elevation view thereof;
 FIG. 7 is a top plan view thereof;
 FIG. 8 is a bottom plan view thereof;
 FIG. 9 is a top, front perspective view of the catheter connector of FIGS. 1-8 in an open configuration;
 FIG. 10 is a bottom, rear perspective view thereof;
 FIG. 11 is a front elevation view thereof;
 FIG. 12 is a rear elevation view thereof;
 FIG. 13 is a right side elevation view thereof;
 FIG. 14 is a left side elevation view thereof;
 FIG. 15 is a top plan view thereof;
 FIG. 16 is a bottom plan view thereof;
 FIG. 17 is a top, front perspective view of a catheter connector in accordance with a second embodiment our new design;
 FIG. 18 is a bottom, rear perspective view thereof;
 FIG. 19 is a front elevation view thereof;
 FIG. 20 is a rear elevation view thereof;
 FIG. 21 is a right side elevation view thereof;
 FIG. 22 is a left side elevation view thereof;
 FIG. 23 is a top plan view thereof;
 FIG. 24 is a bottom plan view thereof;
 FIG. 25 is a top, front perspective view of the catheter connector of FIGS. 17-24 in an open configuration;
 FIG. 26 is a bottom, rear perspective view thereof;
 FIG. 27 is a front elevation view thereof;
 FIG. 28 is a rear elevation view thereof;
 FIG. 29 is a right side elevation view thereof;
 FIG. 30 is a left side elevation view thereof;
 FIG. 31 is a top plan view thereof;
 FIG. 32 is a bottom plan view thereof;
 FIG. 33 is a top, front perspective view of a catheter connector in accordance with a third embodiment of our new design;
 FIG. 34 is a bottom, rear perspective view thereof;
 FIG. 35 is a front elevation view thereof;
 FIG. 36 is a rear elevation view thereof;
 FIG. 37 is a right side elevation view thereof;
 FIG. 38 is a left side elevation view thereof;
 FIG. 39 is a top plan view thereof;
 FIG. 40 is a bottom plan view thereof;
 FIG. 41 is a top, front perspective view of the catheter connector of FIGS. 33-40 in an open configuration;
 FIG. 42 is a bottom, rear perspective view thereof;
 FIG. 43 is a front elevation view thereof;
 FIG. 44 is a rear elevation view thereof;
 FIG. 45 is a right side elevation view thereof;
 FIG. 46 is a left side elevation view thereof;
 FIG. 47 is a top plan view thereof;
 FIG. 48 is a bottom plan view thereof;
 FIG. 49 is a top, front perspective view of a catheter connector in accordance with a fourth embodiment our new design;
 FIG. 50 is a bottom, rear perspective view thereof;
 FIG. 51 is a front elevation view thereof;
 FIG. 52 is a rear elevation view thereof;
 FIG. 53 is a right side elevation view thereof;
 FIG. 54 is a left side elevation view thereof;
 FIG. 55 is a top plan view thereof;
 FIG. 56 is a bottom plan view thereof;

FIG. 57 is a top, front perspective view of the catheter connector of FIGS. 49-56 in an open configuration;

FIG. 58 is a bottom, rear perspective view thereof;

FIG. 59 is a front elevation view thereof;

FIG. 60 is a rear elevation view thereof;

FIG. 61 is a right side elevation view thereof;

FIG. 62 is a left side elevation view thereof;

FIG. 63 is a top plan view thereof; and,

FIG. 64 is a bottom plan view thereof.

The broken lines depict unclaimed subject matter and form no part of the claimed design.
